Primary Examiner — Clare E Heflin(74) *Attorney, Agent, or Firm* — James A. Gavney, Jr.; JAG Patent Services(57) **CLAIM**

We claim the ornamental design for an open channel light fixture, as shown and described.

DESCRIPTION

FIG. 1 is a top perspective view of an open channel light fixture, showing our new design;

FIG. 2 is a top plan view thereof;

FIG. 3 is a front and back view thereof;

FIG. 4 is a bottom view thereof; and,

FIG. 5 is a right and left side view thereof.

The broken lines shown on the drawings depict environment and form no part of the claimed design.
